UNITED STATES PATENT OFFICE.

E MILTON HORTON, OF ALBION, MICHIGAN, ASSIGNOR, BY MESNE ASSIGNMENTS, TO UNION STEEL PRODUCTS COMPANY, OF ALBION, MICHIGAN, A CORPORATION OF MICHIGAN.

SPRAYING MACHINE.

Application filed August 7, 1924. Serial No. 730,762.

To all whom it may concern:

Be it known that I, E MILTON HORTON, a citizen of the United States, residing at Albion, county of Calhoun, State of Michigan, have invented certain new and useful Improvements in Spraying Machines, of which the following is a specification.

This invention relates to improvements in spraying machines.

10 My improved spraying machine is especially designed by me for greasing bakers' pans, although it is desirable and readily adapted for use in other relations, as for washing or sterilizing pans and the like.

15 The main object of this invention is to provide an improved spraying head which is well adapted for handling liquids such as hot grease, is not likely to become clogged, or should it become clogged can be readily cleaned without disassembling.

20 A further object is to provide a machine of the class described which is readily adjusted for different kinds of work.

25 Objects pertaining to details and economies of my invention will definitely appear from the detailed description to follow.

I accomplish the objects of my invention by the devices and means described in the following specification. The invention is 30 clearly defined and pointed out in the claims.

A structure which is a preferred embodiment of my invention is clearly illustrated in the accompanying drawing forming a part of this application, in which:

35 Fig. I is a fragmentary view of a spraying machine embodying the features of my invention as I have adapted the same for pan greasing machines, a spray head being shown in vertical section on a line corresponding to line 1—1 of Fig. II.

40 Fig. II is a fragmentary plan view showing the general arrangement of the spray heads.

Fig. III is a horizontal section on a line corresponding to line 3—3 of Fig. I.

45 Fig. IV is a fragmentary view showing further details of the machine as adapted for greasing pans.

The sectional views are taken looking in 50 the direction of the little arrows at the ends of the section lines and similar numerals of reference refer to similar parts throughout all of the views.

Referring to the drawing, 1 represents a

way or track along which the articles to be sprayed, as the bakers' pans 2, may be pushed. A series of pans is shown in the accompanying drawing connected by the straps 3 as is the usual practice.

55 The spray heads designated generally by the numeral 4 are adjustably supported by the rod 5 to discharge into the inverted pans. 6 represents the grease pan for lard or other material.

60 My improved spray heads comprise the outer or body members 7 having cylindrical chambers 8 therein terminating at the upper end in a conically tapered throat 9 which opens into the countersunk tip 10. The inner member 11 has a threaded portion 12 at its lower end threaded into the lower end 65 of the chamber 8, a cylindrical portion 13 70 and a conical portion 14 fitting within the chamber 8.

75 Between the cylindrical portion and the threaded portion the inner member has a reduced portion 15 providing an annular air passage 16 into which the air conduit 17 opens. The conical portion of the inner member projects through the throat of the outer member and terminates in an outwardly flaring head or tip 18 which is supported in spaced relation to the countersink 10, the cylindrical portion of the inner member having longitudinal grooves 19 therein 80 providing discharge passages, these passages opening to the annular passage 16. The inner member has a longitudinal liquid passage 20 with the branches 21 opening to the discharge passages.

85 The passage 20 of the inner member is connected through the pipe 22 which extends into the grease pan 6. With the parts thus arranged, the air being supplied through the pipe 17, is discharged through the discharge passages, carrying the liquid with it with an atomizer effect. This is discharged 95 upwardly against the deflecting tip 18 and is effectively sprayed out between this tip and the countersink 10.

100 The conduits 17 are provided with flexible portions connected to the air supply pipe 23 through the valves 24. The liquid supply pipe 22 is provided with a screen 25 and has a notch-like opening 22' in spaced 105 relation to its lower end so that when the liquid in the tank or pan 6 falls below a predetermined point, the device becomes in-

operative. This serves as a warning to the operator that the supply of liquid should be replenished.

It will be understood that in pan greasing machines the grease must be kept in fluid condition by heat and if the supply becomes too low in the pan it is charred, or carbon is formed which is likely to clog the nozzles, and it would be objectionable to dis-
5 charge such material into the pans. However, should the nozzle become clogged, to clean it effectively, it is only necessary to place the hand or a pad over the discharge of the nozzle. The air then passes from the
10 discharge through the passages 21 and 25 and the pipe 22, freeing the same from any obstructions.
15

To readily adapt the machine to different sized pans the spray heads are adjustably supported on the rod 5, the outer or body members of the heads being provided with clamp arms 26 and 28 adapted to receive the rod as shown in Fig. I. A bolt 29 engages the clamping wedge 30 disposed in the opening 31 of the arm 28 so that by turning the nut the clamping wedge is drawn against the rod. This provides means whereby the spray heads may be adjusted to the desired position and is a very decided ad-
20 vantage as it will be understood that most bakeries use pans of different sizes.
25

I have illustrated and described my invention in an embodiment which I have found very practical. I have not attempted to illustrate or describe certain embodiments and adaptations which I contemplate as I believe the disclosure made will enable those skilled in the art to which this invention relates to embody or adapt the same as may be desired.
30

Having thus described my invention what I claim as new and desire to secure by Letters Patent, is:

1. In a spray nozzle, the combination of
35 an outer member having a cylindrical chamber therein terminating at one end in a

conically tapered throat opening to a countersunk tip, an inner member threaded into the bottom of said chamber and having a longitudinally grooved cylindrical portion fitting within said chamber, and a conical portion projecting through said throat and spaced from the wall thereof and terminating in a flaring tip spaced from the countersunk tip of said outer member, 50 said inner member having a reduced portion between its cylindrical and threaded portions, said reduced portion and longitudinal grooves coacting with the walls of the chamber providing discharge passages, said 55 chamber having an air connection opening to said passages, said inner member having a longitudinal liquid passage with discharge orifices aligned with said grooves.

2. In a spray nozzle, the combination of 60 an outer member having a cylindrical chamber therein terminating at one end in a conically tapered throat opening to a counter-
65 sunken tip, an inner member having a longitudinally grooved cylindrical portion, and a conical portion projecting through said 70 throat and terminating in a flaring tip spaced from the countersunk tip of said outer member, said grooves coacting with the walls of the chamber providing dis-
75 charge passages, said chamber having an air connection opening to said passages said inner member having a liquid passage open-
ing to said discharge passages.

3. In an apparatus of the class described, so the combination of an air supply pipe, a plurality of spray nozzles having clamp members at one side thereof, a supporting rod with which said clamp members are engaged, whereby the nozzles may be adjusted 85 thereon, flexible conduits connecting said nozzles with said air pipe, a liquid supply tank, and liquid conduits for said spray nozzles depending into said tank.

In witness whereof, I have hereunto set 90 my hand.

E MILTON HORTON.
